UNITED STATES PATENT OFFICE.

ROBERT EMMETT HINCHEY, OF AURORA, MISSOURI.

TWO-STORY MOVING-DISPLAY ADVERTISING MACHINE.

Application filed December 7, 1922. Serial No. 605,515.

To all whom it may concern:

Be it known that I, ROBERT EMMETT HINCHEY, a citizen of the United States, residing at Aurora, in the county of Lawrence and State of Missouri, have invented certain new and useful Improvements in a Two-Story Moving-Display Advertising Machine, of which the following is a specification and is illustrated in the accompanying drawing.

My invention relates to a two-story, moving-display advertising machine, adapted to successively exhibit small merchandise, pictures, display-cards, advertising-sheets, etc. of any size and number desired, and it has particular reference to the advertising device shown in U. S. patent application No. 413,504, filed Sept. 29, 1920, the patent on which has not been granted. Since I desire to patent improvements on the device shown in the aforementioned case, I purpose to present my present application for substitution thereof, and to allow said case No. 413,504 to become abandoned forthwith, in order that I may have the benefit of the filling of said original case in so far as matter common to the two cases is concerned. The aforementioned invention comprises a framework supporting an endless-pathway or track, having oppositely disposed, vertical and transversely horizontal directions, a series of upright, card-display carrying-frames arranged in sets, one above the other, and more bodily movable in opposite directions, the endmost frames being alternately received from and delivered into the vertical card-displaying portions of said endless-track, where they are individually and consecutively transferred from one set to the other and vice versa. While thus being transferred said frames, bearing two displays each, placed in back-to-back, are presented twice on their respective sides opposite openings where they are permitted to pause a suitable interval to display advertisements, etc. thereon. All of these movements are adapted to be intermittent, and are effected by means of two similar endless-chain devices secured to opposing end-walls of said supporting-frame, which are uniformly distanced apart equal to the length or breadth of the display-frames. Said chains are controlled by a continuously-rotated shaft that extends from one device to the other. This apparatus may and preferably will be made durable, inexpensive

and compact, so as to take the least possible space, either inside or out of doors.

For the sake of completeness and clearness of the record it warrants me to call attention to the fact that many features of this machine are similar to the advertising device disclosed in my corresponding application S. N. 413,505, filed Sept. 29, 1920, patented Sept. 12, 1922, No. 1,429,205, and the improvement thereon, application S. N. 581,010, filed Aug. 10, 1922, patented Aug. 21, 1923, No. 1,465,304 which is a one-story device having only horizontal and transverse movements.

The aforesaid supporting-frame with its combination of machinery and sets of movable frames, is to be inclosed in a neat glass cabinet having four display-openings, two on each side, front and rear.

These objects are attained by the mechanism illustrated in the accompanying drawing, (which is not made to scale, but merely to explain the principle and structure of the machine), in which—

Fig. 1 is a left end elevation of the interior of machine; Fig. 2, left end elevation showing the ends of the upper and lower sets of movable display-carrying frames in position for starting; Fig. 3, a front elevation showing interior; Fig. 4, a sectional view of the rear of right end in lower or first section; Fig. 5, sectional view of the rear of right end in upper or second section; Fig. 6, a section of top of left end for large machines that require two sprocket-wheels instead of one; Fig. 7, front of glass cabinet for enclosing the entire mechanism.

Referring to the drawing F. represents a supporting-frame which may be made of metal or any suitable material, divided into two sections, upper and lower or C and D, C first or lower section; D second or upper section. A represents a set or series of movable, display-carrying frames in section C, and B another similar set in section D. These frames may be of the same material as the supporting-frame, each made with a groove all around in the inner part and preferably open at the top to receive cards bearing advertisements, etc. that may be slipped in back-to-back, in order that the exhibits may be presented to view on both sides of the machine. The construction of the supporting-frame F. is such that the sections C and D, each have a front and rear display-opening, making in all

four openings opposite which four different advertisements, etc. may be viewed at all times, each exhibit being exposed twice on its side of the machine.

- 5 Said sections C and D are spaced apart in vertical alinement, with spaces at top 75 and bottom 77 thereof, and an additional space 76 therebetween, supporting oppositely disposed clusters of circuit-makers and
 10 breakers for flashing ornamental colored lights arranged in the said upper and lower spaces 75 and 77, the operation of which will be fully explained hereinafter.

The card-supporting-frames of sets A
 15 and B are movable in what I may term an endless-pathway, the first section C and the second section D constitute the two transverse, horizontal sections or portions, in which one set of frames A are movable, rear-
 20 wardly and bodily, in section C, and the other set of frames B are movable in an opposite direction, forwardly and bodily, in the second section or portion D.

In each instance after the aforementioned
 25 movements, the diagonally opposing endmost-frames 5 are adapted to be transferred singly and consecutively from one set, as A, through the rear vertical portion E', to the other (as B, and vice versa, through the
 30 front vertical card-displaying portion E, to the other set as A, by means of like short slots or notches 4 4' cut oppositely in the outmost edges of said frames 5, adapted to co-operate directly with two like oscillating-
 35 hooks 3 3' that are mounted on similar endless-carrying-chains 1 1', secured to the inner face of opposing end-walls adjacent the ends of said sets of frames 5, A and B.

In Fig. 3, said endless-chain-devices are
 40 operated by opposing sprocket-wheels 2 2', fastened to a gear-shaft J that extends across the machine, and is continuously rotated by the driving-gear K, (any suitable gear may be used), which in turn is operated by the driving-power, preferably an electric-motor L.

Fig. 1 constitutes one of two similar end-walls, showing in detail one endless-chain-device 1 passed about sprocket-wheels 2 and 2' mounted respectively on long shaft J under set A, and short shaft J' adjacent the ends of the upper part of frames in set B. Said sprocket-wheels, so positioned, are adapted to balance and guide said endless-chain 1, in order that a single oscillating-hook 3 mounted thereon, may have co-operation with the several parts of the operative mechanism that are located in its path at suitable intervals, to effect intermittent movement, bodily and singly, of all the frames 5 through said endless-pathway, composed of the transverse portions C and D, and the vertical card-displaying portions E and E'.

As may be seen in Figs. 1 and 2, said end-

less-chain-device 1 is supposed to be continuously in motion, so the above mentioned intermittent movements may be governed by the time it takes hook 3 to travel from one co-operative part to the next, engaging and releasing them in turn, as will hereinafter be more fully described.

With further reference to the drawing, similar numerals refer to similar parts throughout the several views, and as aforesaid include both sides of the mechanism, which are exactly alike, function the same and work simultaneously, but, for the sake of brevity and less confusion I will preferably refer in most part to only one side in describing the operation of the apparatus herein shown. Any of the features described that have corresponding features in the aforesigned Patent No. 1,465,304, Aug. 21, 1923, serve only to make up the present combination, and form no part of the present invention.

As shown in Fig. 2, the sets A and B, of frames 5 are at rest and the displays in the endmost-frames may be supposed to be opposed to be opposite openings in the inclosing case. The shaft J may be supposed to be continuously in motion, turning sprocket-wheel 2, thereby actuating endless-link-chain 1, on which is pivotally mounted an all-purpose operating member—oscillating hook 3—that has a lug at 35, adapted to slide in and be controlled by a special groove-track 37 having curves at given points, directed inwardly at 38, Fig. 4; and outwardly at 39, Fig. 5, to effect said oscillations at determinate positions as will hereinafter be more fully described.

Thus, in Figs. 2 and 4, hook 3 ascends till it is moved inwardly at curve 38, which causes said hook 3 at point 36 to extend through slot 44, Fig. 1, where it is brought substantially into position to engage notch 4 of the endmost-frame 5, for the purpose of elevating said frame 5 from the rear of section C through the vertical portion E', to space 31 in the rear of section D, leaving a similar space 31 in lower section C. As said frame 5 ascends it presses in trigger 6, Figs. 1 and 2; 6 in turn presses in trigger 46 that causes the current connection for flashing the ornamental colored lights 70 in the rear of machine. Said frame 5, in passing, releases trigger 6, whereby trigger 6 springs outwardly to normal position, and thus breaks the circuit in said rear alternating lights 70 and simultaneously places the wide portion of trigger 6, at 48 into position to serve as a rest for said frame 5, and that the finger 48' that is integral with trigger 6 may extend upwardly and beyond the lower edge of said frame 5, the upper edge being kept plumb by an independent spring 47. This last movement may be accomplished by hook 3 having arrived at the out-

ward curve 39, in track 37, Fig. 5, thereby releasing notch 4 and placing said frame 5 in position to be delivered into the rear of the upper section D.

- 5 Hook 3, in passing about sprocket-wheel 2', Fig. 1, engages elbow-lever 49, which is linked by means of a longitudinal-rod 7, to elbow-lever 24; that is connected by means of a link 29, to a flat-hooked-bar 8, that extends 10 across and beyond the edge of the endmost frame 5 at 8' in the front of first section C. These movements cause said hooked-bar 8 with the assistance of automatic curved-spring 54, to effect bodily movement of all 15 the frames 5 in said section C, rearwardly the distance of the thickness of one frame 5, filling the space 31 in the rear of section C, and leaving a similar space 31 in the front of said section C.
- 20 Hook 3 descends to inward curve 41 in the front vertical portion E, Fig. 3, and is thereby caused to engage notch 4 in the upper endmost frame 5 at front of section D, to effect its transfer to space 31 in front of 25 lower section C, leaving a like space 31 in front of section D. Said frame 5, which rests upon curved-spring 53, acts in passing to press outwardly said curved-spring 53 and also curved-spring 54, with a simultaneously pressure inwardly of spring-lever 51, Figs. 1, 2 and 3, which in turn presses in trigger 52, thereby making the contact for 30 flashing the ornamental lights in the front of machine, 72 72', 73 73'. (Fig. 3.)

35 In completing its descent, frame 5 presses yieldable-bar 55 downwardly sufficient for the top of said frame 5 to be below the end of said spring-lever 51, 51', Fig. 3, thus permitting 51, 51' to spring outwardly, thereby 40 breaking the circuit to said alternating lights 72 72', 73 73', and also causes the free end of said lever 51, Fig. 2, to be outside of the upper edge of frame 5 after it has been 45 released by hooks 3, 3' receding from out of notch 4, 4' in the process of passing through outward curve 42, 42' Fig. 3.

Hook 3, in passing about sprocket-wheel 2, Fig. 1, in direction of arrows engages elbow-lever 58, which is linked by means of longitudinal-rod 59 to elbow-lever 16, which in 50 turn connects short rod 26 to trigger 6, having a finger at 48', which extends upwardly and beyond the edge of the endmost frame 5 in the rear of the second section D. These 55 last movements cause trigger 6 with the assistance of independent curved spring 47, near top, to effect bodily movement of all the frames 5 in said section D, forwardly the distance of the thickness of one frame 5, filling the space 31 in the front of said section D, by placing the endmost-frame 5 upon springs 53 and 51, serving at this time as a 60 rest, then leaving a space 31 in the rear of said section D. Thus is completed the cycle of one frame through its endless-pathway,

and these movements are repeated as long as the machine is kept running.

In Fig. 1, rods 7 and 59 have turn-buckles 60 and 61 respectively, to regulate the distance they move their cooperative parts, also stiff-springs 62 and 63 at one end to serve as restraining springs and to prevent breakage. Lever 16 has a slot in the lower arm that allows rod 26 to slide back without moving lever 16 during the time that trigger 6 is being actuated by the pressure of the ascending frame 5. Levers 16, 24, and 58 are returned to their respective positions by means of small coil springs 64, 65, and 66.

Fig. 7 represents the enclosing glass cabinet—front elevation—which has four openings opposite which the moving displays are shown, two in front, W and X, and two in rear, not shown. There are also four openings for stationary transparent displays in front of the ornamental lights, two in front T V, and two in rear, not shown in drawing. In center of cabinet between the sections are oppositely positioned small spaces for stationary ads, one in front U and one in rear, not shown.

Having fully described my invention, what I claim as new and different, and desire to secure by Letters Patent is:

1. The combination in a two-story, moving-display advertising machine, comprising a framework supporting an endless-pathway, provided with a front and rear vertical card-displaying portion and an upper and lower, forwardly and rearwardly inclined, transfer portion, a series of upright card-display carrying-frames divided into upper and lower sets, two opposing endless-chain carrier devices, each running on sprocket-wheels, which are substantially associated and caused to function alike and to work simultaneously, by a continuously-rotated shaft bearing suitable gear extended across the machine, said gear engaging the driving power, and said shaft connecting two of the opposing sprocket-wheels turning them in the same direction, an oscillating hook mounted on each said endless-carrier, adapted to the several tasks of operating the means to transfer said frames, intermittently and consecutively, from one set to the other and vice versa, and to effect intermittent bodily movement of all the frames in opposite horizontal directions, comprising a series of independent mechanisms, rods, levers, and triggers, located directly and indirectly in regulating distances within the path of said hook members and actuated thereby, while said endless-chains are running, substantially as described.

2. The combination in a two-story, moving-display advertising machine, of a supporting frame having a track provided with a front and rear vertical card-displaying portion, and an upper and lower oppositely

inclined horizontal transfer portion; a series of upright card-display carrying-frames divided into upper and lower sets; oppositely positioned endless-chains carrying oscillatory hooks mounted thereon, each hook having a small lug attached thereto, and located externally of said hook members; grooved tracks to receive said lugs, and said tracks having curves directed inwardly and outwardly at determinate positions to control the passage of said hook-members; means for driving said chains to move said frames from one set to the other and vice versa, each frame having reciprocal notches 5 cut oppositely in the outmost edges adapting the diagonally opposed lower and upper endmost frames to co-operate, respectively, with the upwardly and downwardly carried oscillatory hooks to transfer the frame individually through the vertical portions; means to effect intermittent bodily movement of all the frames in the sets in opposite horizontal directions, comprising independent mechanisms arranged directly and indirectly at 10 timing distances in the path of said hooks, which intermittently actuate and release in turn co-operative parts of said independent mechanism, comprising elbow-levers at top that are operatively linked by means of downwardly directed rods and other elbow-levers to hooked-bars that pass horizontally to catch beyond the outmost edges of the endmost frame in the lower vertical portion, operating to press against said frame to 15 effect bodily movement of all the frames in said section; elbow-levers at bottom that are operatively linked by means of upwardly directed rods to other elbow-levers and horizontal rods to spring-triggers having fingers 20 that project upwardly and beyond the lower edge of the upper endmost frame in the rear vertical portion, to serve as a support therefor after said frame has reached the upper limit of motion, and to press against 25 said frame to effect bodily movement, forwardly, of all the frames in said portion, substantially as described.

3. The combination in a two-story, moving-display advertising machine, of a supporting frame provided with a front and rear vertical card-displaying portion, and an upper and lower oppositely inclined horizontal transfer portion; a plurality of card-displaying frames arranged in sets; endless-carrier-chains having oscillatory hooks 30 mounted thereon and means for driving said chains; said frames having co-operative notches cut oppositely in the outmost edges for cooperation with said hooks to move said frames vertically: means for moving said frames transversely; said transfer portions communicating at front and rear thereby forming an endless track through which said frames are movable in vertical and transverse directions; a device having sections spaced apart in vertical alinement, with spaces at top and bottom thereof, and an additional space therebetween supporting oppositely disposed clusters of circuit makers and breakers for flashing ornamental colored lights that are mounted in the upper and lower said spaces, and connected electrically with said clusters having contacts arranged adjacent the means for making said flashes, comprising small triggers adjusted 35 relative to said contacts, oppositely, and secured to spring-triggers that yieldingly extend into the rear vertical portion, and to elongated spring-levers having free ends projecting into the front vertical portion, adapted to be actuated intermittently and determinately by the pressure of the ascending and descending frames in passing consecutively therethrough, substantially as described.

In testimony whereof I have signed my name to this specification.

ROBERT EMMETT HINCHEY
